(57) **CLAIM**

The ornamental design for a combination ceiling fan blade and blade attachment assembly, as shown and described.

DESCRIPTION

FIG. 1 is a perspective view from below of a combination ceiling fan blade and blade attachment assembly in accordance with my design, including the environment thereof; FIG. 2 is a perspective view from below of the combination ceiling fan blade and blade attachment assembly in accordance with my design;

FIG. 3 is an enlarged perspective view of the combination ceiling fan blade and blade attachment assembly in accordance with my design;

FIG. 4 is a bottom plan view of the combination ceiling fan blade and blade attachment assembly in accordance with my design;

FIG. 5 is a top plan view of the combination ceiling fan blade and blade attachment assembly in accordance with my design;

FIG. 6 is a rear end view of the combination ceiling fan blade and blade attachment assembly in accordance with my design; and,

FIG. 7 is a front end view of the combination ceiling fan blade and blade attachment assembly in accordance with my design.

The broken lines showing environmental structure are for illustrative purposes and form no part of the claimed design. In FIG. 3 the fan blade is shown broken away to indicate indeterminate length.
